DESIGN FOR A FOUNTAIN BRUSH

Julian H. Bair, Seattle, Wash.

Application April 21, 1941, Serial No. 100,533

Term of patent 7 years

To all whom it may concern:

Be it known that I, Julian H. Bair, a citizen of the United States, residing at Seattle, in the county of King and State of Washington, have invented a new, original, and ornamental Design for a Fountain Brush, of which the following is a specification, reference being had to the accompanying drawing, forming part thereof.

I claim:

The ornamental design for a fountain brush, as shown.

JULIAN H. BAIR.
